ESTABLISHED

UNITED STATES PATENT OFFICE.

CLARENCE B. SCHULTZ, OF CHARLOTTENBURG, GERMANY.

CUTTING DEVICE FOR CIGAR-ROLLING MACHINES.

SPECIFICATION forming part of Letters Patent No. 634,481, dated October 10, 1899.

Application filed December 14, 1896. Serial No. 615,589. (No model.)

To all whom it may concern:

Be it known that I, CLARENCE B. SCHULTZ, engineer, a citizen of the United States, residing at Charlottenburg, in the Province of Brandenburg, Prussia, German Empire, have invented certain new and useful Improvements in Cutting Devices for Cigar-Rolling Machines, for which I have obtained Letters Patent in Germany, No. 94,937, dated October 31, 1896; in France, No. 260,896, dated October 31, 1896; in Belgium, No. 124,295, dated October 31, 1896; in Luxemburg, No. 2,645, dated November 2, 1896; in England, No. 27,178, dated November 30, 1896; in Switzerland, No. 13,514, dated November 30, 1896; in Norway, No. 6,076, dated December 4, 1896; in Hungary, No. 12,410, dated January 31, 1898; in Austria, No. 48/1,147, dated February 18, 1898; in Spain, No. 22,216, dated March 24, 1898, and in Italy, No. 34/47,216, dated March 31, 1898;) and I do hereby declare the following to be a full, clear, and exact description of the invention, such as will enable others skilled in the art to which it appertains to make and use the same.

My invention consists of means whereby the tuck of a cigar may be cut sharp and straight across without breaking the wrapper, as will be hereinafter set forth.

Figure 1 represents a partial elevation and partial vertical section of a cutting device of a cigar rolling or making machine embodying my invention. Fig. 2 represents a section on line $x-x$, Fig. 1. Figs. 3 and 4 represent side elevations of the blades or knives and their carriers. Fig. 5 represents a side elevation of the machine with its various parts in assembled position. Fig. 6 represents a plan view of certain of the parts shown in Fig. 5. Fig. 7 represents an end elevation of jaws employed for retaining a cigar in the machine while its end is being cut.

Similar letters of reference indicate corresponding parts in the several figures.

Referring to the drawings, a and b designate two bars or stocks which, placed side by side, carry the concave knives or blades a' b' , respectively, and are guided in grooves g in the frame m , the knife a' being adapted to be brought up close to the cigar z to be cut, while the other knife b' is adapted to shear or cut squarely across the same, for which purpose

it is desirable to move the bars a b in order to advance the knives and then to separate or open the same. For this purpose I employ the driving-shaft o and provide the bar a with the hanger a^2 , on one side of which are the double levers e and the pin k , said levers being connected with said hanger by the screw f .

In the bar a is the longitudinally-extending slot a^3 , in which freely enters the stud l on the bar b .

Bearing against the lever e is the spring v for keeping said lever against the stud l . Mounted on the stud d is the elbow-lever c , the same resting upon the stud t on the lever e and having the horn c' projecting therefrom.

h designates a lever which swings on the screw or stud u on the bar b and has its lower end forked and entering the groove r in the segment q , the latter being keyed or otherwise secured to the shaft o . Beside the lever h is the link i , which swings on the stud u and has a slot which receives the stud k of the bar a .

s designates a nose on the frame of the machine, the same being adapted to be struck by the link i .

On the side of the segment q are two studs n and p , which are so disposed that when the segment is turned the stud n pushes the lever e , and with it the bar a , to the right until the shoulder a^4 on the bar a reaches the guide g , when the bar b is pushed to the left, whereby the knife a' is moved up to the cigar and the knife b' passes straight across the same, cutting the tuck. Then the stud p strikes the forked lever h and draws the bar b by the screw or stud u again to the right until the shoulder b^4 on the bar b strikes the guide g . The bar a is pushed simultaneously by means of the link i to the left, when the knives open or separate and the cigar may be removed and a new bunch or cigar supplied.

The cigar z is placed between the jaws z' and z^2 when said jaws are in their opened position, as shown in dotted lines in Fig. 7. The jaws z' and z^2 when in their closed position, as shown in full lines in Fig. 7, firmly retain the cigar z in position while its end is being cut by the knives or blades a' and b' .

The jaws z' and z^2 are opened and closed at the proper intervals through the action of the rods a^6 , which latter are secured to the pinions b^6 near the peripheries thereof, so that

as the said pinions rotate the rods a^6 will be carried around by them, causing the jaws z^1 and z^2 , whose lower bifurcated extremities c^4 straddle the said rods, to be actuated so as to alternately open and close the jaws, as will be readily apparent.

The jaws z^2 are retained in their normal positions by springs c^2 , and the object of said springs is to permit the jaws z^2 to close 10 more or less, according to the varying thicknesses of the cigars placed between them and the jaws z' , it being evident that by these means all danger of crushing a cigar is removed, it being also apparent that if said 15 jaws z^2 were rigid the same would crush a cigar if the latter were thicker than the space between the jaws z' and z^2 .

The pinions b^6 are driven by the spur-wheels d^4 on the main driving-shaft e^4 .

20 In contemporaneously-pending applications filed by me December 14, 1896, bearing Serial Nos. 615,588 and 615,590, I have shown and described certain features of mechanism to which I herein make no claim.

25 The devices herewith shown for moving the cigar or bunch of tobacco toward the tip-shaper are claimed in another application for Letters Patent filed December 14, 1896, Serial No. 615,590.

30 Having thus described my invention, what I claim as new, and desire to secure by Letters Patent, is—

1. A cutting device for a cigar consisting of bars, and a knife on each of the same, said 35 bars being adapted to move in opposite directions, and means for causing one knife to ap-

SECTION, COMMERCIAL, 1910-1911

proach the cigar and temporarily stop in proximity thereto, and means for causing said other knife to continue its movement and shear the same.

2. In a device substantially as described, the coacting knives a' and b' , the lever h , and the double lever e for opening and closing the knives a' , b' , a rotatable shaft, connections common to said shaft and levers for operating the latter, and means for temporarily interrupting the progression of one knife, while the other knife continues its movement.

3. In a device substantially as described, the segment *q* having studs *n* and *p* thereon, the lever *h*, the lever *e* and the link *i*, knives adapted to move in opposite directions, and connecting mechanism intermediate said levers and knives.

4. In a device substantially as described, the lever *i*, and the nose *s* on the frame *m*, in combination with the opening-and-closing knives, the latter being adapted to move in opposite directions, and means for actuating said lever and knives.

5. In a device substantially as described, the combination of the lever *e* with the stud *t*, the elbow-lever *c* the opening-and-closing knives, the latter moving in opposite directions, and means for operating said levers and knives.

... In witness whereof I have hereunto signed
my name in the presence of two witnesses. ...

CLARENCE B. SCHULTZ
